US0D1043372S

(12) **United States Design Patent** (10) **Patent No.:** **US D1,043,372 S**
(45) **Date of Patent:** **** Sep. 24, 2024**

(54) **CASE FOR ELECTRONIC DEVICE**

(71) Applicant: **SPIGEN KOREA CO., LTD.**, Seoul (KR)

(72) Inventor: **Yuseon Choe**, Seoul (KR)

(73) Assignee: **SPIGEN KOREA CO., LTD.**, Seoul (KR)

(**) Term: **15 Years**

(21) Appl. No.: **29/867,855**

(22) Filed: **Nov. 10, 2022**

(51) LOC (14) Cl. **10-02**

(52) U.S. Cl.

USPC **D10/30**

(58) **Field of Classification Search**

USPC .... D14/138 R, 344; D10/30, 31, 32, 38, 70, D10/128, 132; D11/3; D24/167 CPC G04G 17/00; G04G 17/08; G04G 17/083; G04G 17/045; G04G 21/00; G04G 21/02; G04G 21/025; G04G 21/06; G04G 21/08; G04G 99/006; G06F 1/163; A44C 5/00; A44C 5/02; A44C 5/022; A44C 5/025; A44C 5/0007; A44C 5/0015; A44C 5/0046; A44C 5/0053; A44C 5/2052; A44C 5/2071; A44C 9/00; A44C 9/0053

(57) **CLAIM**

The ornamental design for a case for electronic device, as shown and described.

DESCRIPTION

FIG. 1 is a front perspective view of a case for electronic device, showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a front perspective exploded view of the case for electronic device of FIG. 1.

The broken lines throughout the drawing figures depict portions of the case for electronic device that form no part of the claimed design. The broken lines and regions bounded by broken lines form no part of the claimed design.

1 Claim, 9 Drawing Sheets
